UNITED STATES PATENT OFFICE

JOSEPH DI SILVESTRO, OF LANCASTER, PENNSYLVANIA

DESIGN FOR A FLOOR LAMP

Application filed September 24, 1929. Serial No. 32,850. Term of patent 3½ years.

To all whom it may concern:

Be it known that I, JOSEPH DI SILVESTRO, a citizen of the United States, residing at Lancaster, in the county of Lancaster and State of Pennsylvania, have invented a new, original, and ornamental Design for Floor Lamps, of which the following is a specification, reference being had to the accompanying drawing, forming part thereof.

I claim:

The ornamental design for a floor lamp, substantially as shown.

JOSEPH DI SILVESTRO.
